UNITED STATES PATENT OFFICE.

HARRY SHULMAN AND FRANK JOERGER, OF BROOKLYN, NEW YORK.

NAILLESS PAINTERBRUSH.

Application filed December 13, 1921. Serial No. 521,981.

To all whom it may concern:

Be it known that we, HARRY SHULMAN, residing at Brooklyn, county of Kings, and State of New York, and FRANK JOERGER, residing at Brooklyn, county of Kings, and State of New York, both citizens of the United States, have invented certain new and useful Improvements in Nailless Paint-brushes, fully described and represented in the following specification and the accompanying drawings, forming a part of the same.

The present invention relates to a flat paint brush having a tuft of bristles glued within one end of a ferrule and a handle fitted within the other end, and a flat ferrule thus enclosing the handle and bristle-tufts at their junction.

The improvement consists in pressing a row of studs, with a suitable multiple pointed tool, from the metal of the ferrule into the substance of the handle and bristle-tufts.

Such rows of studs very strongly engage the wood of the handle and the bristle-tufts, so that neither is liable to be loosened from the ferrule.

By the present improvement, the ferrule, when the parts of the brush are assembled, is subjected at the end embracing the handle to opposed rows of tapering punches which press rows of conical studs from the ferrule into the substance of the handle upon both sides of the ferrule simultaneously.

A repetition of the operation upon the opposite end of the ferrule serves to press the studs into the tuft of bristles, and the handle and tuft are thus securely and permanently locked within the ferrule.

The invention will be understood by reference to the annexed drawing, in which Fig. 1 shows one side of a flat brush provided with the improvement; Fig. 2 is a perspective view of the ferrule in readiness for the application of the handle and bristles thereto; Fig. 3 is a longitudinal section on line 3—3 in Fig. 1 showing the indentation of the studs into the substance of the handle and bristles; Fig. 4 is a section on line 4—4 in Fig. 1; and Fig. 5 is a perspective view of one of the dies for pressing the studs from the metal of the ferrule.

Fig. 1 shows the brush provided with the ferrule 6, the handle 7 and bristle-tuft 8.

The ferrule in the finished brush shown

in Fig. 1 has two rows of indentations 9 there- 55 in near its opposite ends, such indentations forming studs 10 which are shown in Fig. 3 pressed into the wood and bristles respectively, near the opposite ends of the ferrule.

Figure 5 shows one of the dies 11 formed 60 with a row of punches 12 upon one edge, such dies being used in pairs with the punches opposite to one another.

Such dies can be mounted in an ordinary foot-press, and when the parts of the brush 65 are assembled with the handle and tuft inserted in the ferrule which embraces the handle is placed between the dies, and the opposed rows of studs formed in the ferrule, permanently indenting the opposite 70 sides of the handle as shown in Fig. 3. When the ferrule is thus locked to the handle, the opposite end of the ferrule is subjected to the same dies, and the studs pressed into the bristle-tufts, securing them most effectively in the ferrule.

Two rows of studs are shown, to avoid crowding the holes together in a single row, which would bring the holes so close together that the studs would not operate individually in grasping the bristles. To obtain an individual effect from each stud, the holes in the adjacent rows are alternated in their respective rows, to operate on the bristles at different distances from the ends 85 of the bristles.

In the manufacture of brushes according to this invention, it is common to secure the shank of the bristles together with glue when fitted in the ferrule, and glue is allowed 90 to harden considerably before the studs are indented from the ferrule into the opposite sides of the bristle-tufts.

The ferrule is completely shaped as shown in Fig. 2 before the adjacent ends of 95 the handle and bristles are inserted therein; and the only labor required after the parts are assembled is to subject the opposite end- portions of the ferrule to the dies which form the studs therein; and this operation 100 is exceedingly brief, and operates much more effectively and accurately to lock the parts together than the nails heretofore used; and the construction also greatly stiffens the ends of the ferrule so that they 105 cling closely to the wood and bristles.

It will thus be seen that the invention reduces the cost of the brush, and improves

its appearance and quality, while securing a better finish and more permanent engagement of the bristles to the handle.

Having thus set forth the nature of the invention what is claimed herein is:

1. The method of securing a flat tuft of bristles within a sheet-metal ferrule, which consists in gluing together one end of the bristles assembled in the form desired for the tuft, and permitting said glue to harden, then fitting a flat-sided ferrule upon the said tuft and pressing rows of studs from the metal of the ferrule into the substance of the cemented bristles.

15 2. The method of securing a flat tuft of

bristles within a sheet-metal ferrule, which consists in gluing together one end of the bristles assembled in the form desired for the tuft, and permitting said glue to harden, then fitting a flat-sided ferrule upon the 20 said tuft and pressing two rows of studs from the metal of the ferrule into the substance of the cemented bristles, the indentations in one row being alternated with those of the adjacent row.

25 In testimony whereof we have hereunto set our hands.

HARRY SHULMAN,
FRANK JOERGER.
